UNITED STATES PATENT OFFICE.

CHARLES KAHLHOFER, OF CENTRALIA, ILLINOIS.

BUCKLE.

SPECIFICATION forming part of Letters Patent No. 314,452, dated March 24, 1885.

Application filed January 22, 1885. (No model.)

To all whom it may concern:

Be it known that I, CHARLES KAHLHOFER, a citizen of the United States, residing at Centralia, in the county of Marion and State of Illinois, have invented a new and useful Improvement in Buckles, of which the following is a specification, reference being had to the accompanying drawings.

My invention relates to a fastening for shoes, and is designed more especially to be applied to what are known as "low-cut" shoes and overshoes, which are usually held in place upon the foot of the wearer by a buckle or like connection.

15 The invention has for its object the production of a fastening of the character described which shall be neat and attractive in appearance, one that may be almost instantly fastened and with but little trouble, and, further, 20 to provide a fastening which may be manufactured and supplied at a slight cost, and one that may be readily and easily applied.

With these ends in view the invention consists in the combination, with an attaching 25 plate or plates, of a pivoted sectional fastening.

The invention further consists in the improved construction and combinations of parts hereinafter fully described, and pointed out in the claims.

30 In the drawings, Figure 1 is a perspective view of a shoe, showing my improved fastening applied thereto. Fig. 2 is a longitudinal vertical section, and Fig. 3 is a detail view in perspective of one of the plates to which my 35 improved fastening is attached at one end.

In the accompanying drawings, in which like letters of reference indicate corresponding parts in all the figures, A represents a shoe.

B represents a metal plate having the prongs 40 or spurs *a* formed integral therewith, said plate being adapted to be attached to one side or flap of the shoe by passing the prongs or spurs *a* through the same, and then bending them upon the inside of the flap of said shoe, thus 45 firmly securing the plate in place.

C represents a plate having a slot or cut-out portion, *b*, at its inner end, in which slot or cut-out portion the inner end of the plate B is inserted, and then bent back upon itself to 50 form a bearing for the plate C, thus pivotally

securing said plates together. The plate C is curved inwardly slightly, and is pivoted at its outer end to the fastening-plate D, a slot being formed at the outer end of said fastening-plate D, and the outer end of the plate C bent 55 around the same to form a pivotal connection. The fastening-plate D is convexo-concave, and is provided with downwardly-extending side flanges, *d*, and at its inner end with an extension or projection bent to form a hook, *e*. 60

E represents a plate which is adapted to be attached to the other or opposite flap of the shoe to that mentioned. The said plate E is provided with prongs or spurs *f*, which are adapted to be passed through the flap and 65 bent upon the same to secure the flap in place. The said plate E is provided with a series of slots, *g*, thus forming cross-bars *h*, to any one of which the hook upon the plate D may be attached. 70

In operation the convexo-concave plate C rests within the convexo-concave plate D, the side flanges of said plate D preventing any lateral movement of the plate C. The hook on the end of the plate D is engaged with any one 75 of the series of bars *h*, thus completing the fastening.

To remove the shoe, the pivoted end of the plate D is raised, thus removing the plate C therefrom and allowing the flaps to be drawn 80 apart a sufficient distance to allow of the removal of the shoe; and to fasten the shoe after it has been adjusted upon the foot the plate D is slightly raised and pushed toward the plate B, thus causing the plate C to drop in 85 the seat upon the under side of the plate D, and as the line of draft is on a line with the pivotal connection of the plate D it is impossible for the fastening to become detached without first raising said plate D. 90

As many of the before-described fastening devices may be employed upon a shoe as is necessary; but ordinarily one will suffice.

The improvement described is simple in its construction, neat and attractive in appearance, may be manufactured and supplied at a comparatively slight cost, is effective in its operation, and by its employment a shoe may be fastened or unfastened in the minimum amount 95 of time. 100

Having fully described my invention, what I claim as new, and desire to secure by Letters Patent, is—

1. The combination, with an attaching-plate, of a pivoted sectional fastening consisting of two plates pivoted together, and pivotally connected with the attaching-plate, one of said plates having side flanges and a hook at its end, and a plate having a series of cross-bars, substantially as set forth.
2. The combination, with an attaching-plate, of convexo-concave plates pivoted together and pivotally connected to said attaching-plate, one of said plates having side flanges, a hook on one of said plates, and a plate adapted to receive said hook, as set forth.

3. The herein-described shoe-fastening, consisting of an attaching-plate, a convexo-concave plate pivoted thereto, a convexo-concave plate pivoted to the plate C, side flanges on said plate D, a hook on said plate, and a plate, E, having means, substantially as described, for its attachment, and a series of cross-bars adapted to be engaged by the hook on the plate D, substantially as set forth.

In testimony that I claim the foregoing as my own I have hereto affixed my signature in presence of two witnesses.

CHARLES KAHLHOFER.
